UNITED STATES PATENT OFFICE.

FRED A. BUSWELL, OF CHATTANOOGA, OKLAHOMA.

REPAIRING-TOOL FOR BARB-WIRE FENCES.

1,207,367.

Specification of Letters Patent.

Patented Dec. 5, 1916.

Application filed November 9, 1915, Serial No. 60,524. Renewed September 27, 1916. Serial No. 122,560.

To all whom it may concern:

Be it known that I, FRED A. BUSWELL, a citizen of the United States, residing at Chattanooga, in the county of Comanche 5 and State of Oklahoma, have invented certain new and useful Improvements in Repairing-Tools for Barb-Wire Fences; and I do hereby declare the following to be a full, clear, and exact description of the invention, such as will enable others skilled in the art to which it appertains to make and use the same.

This invention relates to repairing tools and is more particularly adapted for repairing barb wire and other wire fences.

One of the objects of this invention is the provision of a repairing tool which is adapted for securing the wire to posts, mending broken strands of wire, tightening slack wire, driving staples for securing the wire to posts, and withdrawing the staples when necessary.

Another object of this invention is the provision of a repairing tool of a single structure capable of many uses, which is light and simple in construction, efficient and durable, and which can be manufactured at a nominal cost.

Other objects and advantages will be hereinafter more clearly set forth in the specification, defined in the claims, and illustrated in the accompanying drawings, in which,

Figure 1 is a perspective view of the device showing the same in the act of securing a strand of wire to a post. Fig. 2 is a side view of the device. Fig. 3 is a vertical sectional view, partly broken away, on line 3—3 of Fig. 2. Fig. 4 is a cross sectional view on line 4—4 of Fig. 2. Fig. 5 is a cross sectional view on line 5—5 of Fig. 2.

Referring to the drawings, the tool is preferably formed of one piece of suitable material. One end of the tool is enlarged to provide the tool end and handle 1. The inner end portion of the handle 1 is preferably reduced in size at 2, and then bent at 3 to provide the short laterally extending arm 4. The arm 4 is disposed substantially at right angles to the handle 1, and is then curved downwardly to provide the U-shaped portion or head 5, the head 5 being substantially in a plane parallel to the handle 1. The head 5 is thickened, and has formed upon its outer side the

hammer head 6. Extending from one side of the head 5, and parallel to the arm 4, is the elongated arm 7. The arm 7 is substantially twice the length of the arm 4, and is provided with the curved upturned pointed end 8, having its outer side edge beveled to provide the sharp edge or blade 9.

In the end of the handle 1 is formed the transverse slot 10, extending into the end of the handle 1 for a distance, and substantially parallel to the arms 4 and 7. Formed through the handle 1 adjacent its free end is the bore 11 passing through the slot 10 at right angles to the slot. Formed transversely in the handle 1 below the bottom of the slot 10, is the enlarged bore 12, and beneath the bore 12 is also formed the smaller transverse bore 13. The bores 12 and 13 extend almost entirely through the handle 1, terminating a short distance from the opposite side of the handle.

The uses to which the tool is adapted for building and repairing wire fences are briefly stated as follows:—When it is desired to use the tool to drive staples and the like, the handle 1 is grasped by the hand of the user and the staple or the like may be efficiently driven into the post or support by the hammer head 6. Should it be desired to withdraw a staple the pointed end 8 of the elongated arm 7 is forced between the wire in the staple and the post and by bearing against the handle 1 the staple may be efficiently withdrawn from the post, and to guard against the cutting of the fence wire when forcing the end 8 between the fence wire in the staple and the post the sharpened edge or blade 9 is provided, so that the blade 9 will cut its way into the post a sufficient distance to permit the insertion of the end 8 of the arm 7 between the fence wire in the staple and the post and thus readily withdraw the staple without injury to the fence wire.

When it is necessary to loop the end of a wire strand or the broken end of a strand, the end of the wire is folded upon itself and the two contiguous portions of the wire, as shown at 14 in Fig. 3, are inserted in the slot 10, and then by twisting the end around the wire in a transverse direction, the contiguous portions 14 being held in the slot 10, the loop is formed. A loop is similarly formed upon the other end of the broken strand and the loops are then

connected together by looping one end of a short piece of wire through one of the loops of the broken strand and twisting the end of the short wire around its body portion by injecting the end into the socket 12 or 13 of the tool and revolving the tool transversely around the wire, and subsequently passing the other end of the short wire through the other loop of the broken strand and injecting this end of the short wire into the socket 12 or 13 and winding this end of the short wire around the handle of the tool for drawing the wire taut, and when sufficiently taut, revolving the tool transversely around the wire for twisting this end of the short wire around its body portion for securing the broken ends of the main strand together. For taking up the slack in the main strand of wire between the posts, one end of the short piece of wire used for this purpose is passed through the bore 11, and the body portion of the short wire adjacent the tool is placed over the main strand and the tool revolved around the main strand for wrapping this end of the short wire therearound, and subsequently the opposite end of the short strand is likewise passed through the bore 11 and carried to another portion of the main strand and likewise secured to the main strand. For securing the main strand wire 15 to the post 16, as shown in Fig. 1, the short piece of wire 17 is used, and either the bore 12 or the bore 13 of the tool is employed, in accordance with the size of the wire used, and in this instance the end of the short wire 17 is inserted in the bore 12, or 13 as the case may be, and the tool revolved around the main wire 15 for twisting the

ends of the short wire 17 at both sides of the post, as shown at 18, around the main wire 15 as clearly shown in Fig. 1, the tool being shown in the act of twisting the second end of the wire 17. This same operation may also be employed for taking up slack in a main strand which has been previously stabled to the post in the usual manner.

While I have here shown the preferred form of the repairing tool, minor variations and alterations may be made therein without departing from the spirit of the invention or the scope of the claims.

Having described my invention, what I claim as new and desire to secure by Letters-Patent, is:—

A repairing tool for wire fences, comprising a straight shank provided with an enlarged portion at one end, and a U-shaped portion projecting laterally from its opposite end and disposed right angularly to the longitudinal axis of the shank, one of the arms of said U-shaped portion being substantially twice the length of the complementary arm and extending transversely across the line of the longitudinal axis of the shank to provide a hand hold for manipulating the shank, the enlarged end of the shank being provided with a plurality of bores to provide means for manipulating the ends of the wire during the repairing operation.

In testimony whereof I have signed my name to this specification in the presence of two subscribing witnesses.

FRED A. THOMAS.
